UNITED STATES PATENT OFFICE.

JOHN PREIZER, OF MONACA, PENNSYLVANIA.

CUSHIONED HEEL FOR FOOT-GEAR.

1,112,932.

Specification of Letters Patent.

Patented Oct. 6, 1914.

Application filed June 1, 1914. Serial No. 842,147.

To all whom it may concern:

Be it known that I, JOHN PREIZER, a subject of the King of Hungary, residing at Monaca, in the county of Beaver and State of Pennsylvania, have invented certain new and useful Improvements in Cushioned Heels for Foot-Gear, of which the following is a specification, reference being had therein to the accompanying drawing.

10 This invention relates to cushioned heels, for footgear, and has for its object to provide a heel of such class, possessing resilient characteristics insuring comfort when walking.

15 Further objects of the invention are to provide a cushioned heel for foot gear, which is comparatively simple in its construction and arrangement, strong, durable, efficient and convenient in its use, readily set up, and comparatively inexpensive to manufacture.

20 With the foregoing and other objects in view, the invention consists of the novel construction, combination and arrangement of parts as hereinafter more specifically described and illustrated in the accompanying drawings, wherein is shown an embodiment of the invention, but it is to be understood that changes, variations and modifications 25 can be resorted to which come within the scope of the claims hereunto appended.

25 In the drawings wherein like reference characters denote corresponding parts throughout the several views:—Figure 1 is 30 a longitudinal sectional view of a portion of a shoe showing the adaptation therewith of a cushioned heel in accordance with this invention, Fig. 2 is a sectional plan of a heel, Figs. 3, 4, 5 and 6 are perspective views of 35 certain elements of the heel.

40 Referring to the drawings in detail, 7 denotes the sole of a shoe and 8 the upper. Secured to the rear end of the sole 7 is a cushioned heel in accordance with this invention and the said heel comprises a series of leather lifts 9, 10, 11, 12, a tread lift 45 13 and a metallic plate 14. The lift 9 is fixedly secured to the sole 7 by the holdfast devices 15 and the lifts 9, 10, 11 and 12 are secured together in a known manner. The 50 lifts 9, 10, 11 and 12 are each provided with a centrally disposed opening 16. The openings 16 register with each other to provide a pocket which is closed at its top, by a disk 55 17 fixedly secured to the sole 7 by holdfast devices 8. The disk 17 is of greater diameter

than the opening 16 and is seated in the top of the lift 9 and lower face of the sole 7.

The reference character 19 denotes a 60 leather band, which conforms in contour to the shape of the heel and is provided at its top with an inwardly extending flange 20 and at its bottom with an inwardly extending annular flange 21. The flange 21 is of less width than the flange 20, and is secured to the lower face of the lift 12 by holdfast devices 22. The height of the band 19 is greater than a plurality of lifts and when said band 19 is secured in position it provides a chamber 23. The flange 21 is interposed between the tread lift 13 and metallic plate 14, and the latter is secured to the former by holdfast devices 24, these latter extending through the flange 21 for fixedly securing it to the lift 13 and plate 19. The plate 19 centrally thereof, is formed with an opening 25 having the wall thereof threaded and extending down through said opening 25, as well as engaging with the threads 70 of the wall of said opening and further abutting against the lift 23 is a peripherally threaded shank 26.

75 Formed integral with the shank 26 is a vertically disposed cylindrical casing 27 80 having opposed vertically disposed slots 28. The casing 20 extends up into the pocket formed by the opening 16 in the lifts 9 to 12.

85 Formed integral with the disk 17 is a plunger 29 provided with a pin 30, which 90 has the ends thereof extend through the slots 28 whereby the end walls of said slots will limit the movement in both directions of the plunger 29.

95 Surrounding the casing 27, bearing against the plate 14 and extending up into the pocket formed by the opening 16 to the bearing against the disk 17 is a coiled spring 31, which maintains the band 19 extended and which further provides for the heel having a cushioning function when a person is walking.

100 What I claim is:—

1. A cushioned heel comprising a plurality of upper lifts provided with registering 105 openings, a plunger fixedly secured within said openings, a lower lift, a metallic plate and a flexible band interposed between said upper lifts and said lower lifts, means for securing said band in position and for further securing said plate to said lower lifts, 110 a cylinder secured to said plate and in which

operates said plunger, and a coiled spring arranged within said opening and engaging said plate for supporting said lower lift.

2. A cushioned heel comprising a plurality of upper lifts arranged to be secured to the sole of a shoe and provided with a pocket, means for closing the top of said pocket, a plunger carried by said means, a lower lift, a metallic plate interposed between the upper and lower lifts, a cylinder having said plunger operating therein and connected with said lower lift, a flexible

member interposed between said upper lifts and said lower lift, and an elastic element for maintaining said lower lift extended, 15 said elastic element surrounding said cylinder and bearing against the means for closing the upper end of said pocket.

In testimony whereof I affix my signature in the presence of two witnesses.

JOHN PREIZER.
